United States Patent Office.

ANDREW AND WILFRED DUNWORTH, OF DOBB'S FERRY, NEW YORK.

Design No. 2,601, dated March 19, 1867.

DESIGN FOR A PITCHER.

The Schedule referred to in these Letters Patent and making part of the same.

TO ALL WHOM IT MAY CONCERN:

Be it known that we, ANDREW DUNWORTH and WILFRED DUNWORTH, of Dobb's Ferry, Westchester county, New York, have invented an improved Design for Plated Ware, &c.; and we do hereby declare that the following is a full, clear, and exact description thereof, which will enable others skilled in the art to understand the same, reference being had to the accompanying drawing, forming part of this specification.

This invention relates to a new design for pitchers, tea sets, and other articles made of Britannia or plated ware, or other metal or substance.

The drawing is a side elevation of a pitcher illustrating our invention.

The body *a* of the pitcher has a pyramidal form, tapering from the base toward the top, as shown. It has four sides or faces, which are joined at right angles. It is ornamented by mouldings, *b*, around the top and bottom, and by corner pieces, *c*, terminating in ornamental supports, *d*, as shown. The beak *e* and handle *f*, as well as the cover *g*, are ornamental, as shown, and the sides or faces of the article are formed in panels.

Having thus described our invention, we claim as new, and desire to secure by Letters Patent—

The ornamental design herein shown and described.

ANDREW DUNWORTH,
WILFRED DUNWORTH.
